(57) **CLAIM**

The ornamental design for an X-ray digital photographing device, as shown and described.

DESCRIPTION

FIG. 1 is a bottom, front, right perspective view of an X-ray digital photographing device, showing the new design;

FIG. 2 is a bottom, rear, left perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is an enlarged view of detail “9” identified in FIG. 3, for clarity of disclosure;

FIG. 10 is a sectional elevation view of the X-ray digital photographing device of FIG. 1, taken along line 10-10 of FIG. 3; and,

FIG. 11 is an enlarged view of detail “11” identified in FIG. 10, for clarity of disclosure.

In the drawings, the equal-length broken lines depict portions of the X-ray digital photographing device that form no part of the claimed design. The broken lines shown in a dot-dash-dot pattern are only used to designate an area that is enlarged in another figure and form no part of the claimed design.
